UNITED STATES PATENT OFFICE

SAMUEL J. WOLFSON, OF EVERETT, MASSACHUSETTS, ASSIGNOR, BY DIRECT AND MESNE ASSIGNMENTS, TO CONCRETE-WOOD FLOOR CLIP COMPANY, INC., OF CHARLES-TOWN, MASSACHUSETTS, A CORPORATION OF MASSACHUSETTS

FLOORING AND THE LIKE

Application filed June 10, 1930. Serial No. 460,189.

The present invention relates, generically, to composite wooden surfaces, such as wall panelling, flooring (strip, parquet, etc.), and the like. More particularly, this invention has especial relation to a fastener for that type of composite wooden surface which is adapted to be laid on underfloorings or backings of concrete and similar material.

It is a common experience in the flooring trade to find that in strip flooring laid upon concrete underflooring there is a marked tendency for the strips to separate from each other and to leave relatively large and unsightly crevices therebetween. This has been partially overcome by the use of an intermediate layer of wood between the concrete backing member and the surface flooring, the latter being nailed or otherwise secured to the intermediate layer. The use of the intermediate layer is, of course, expensive and involves the expenditure of additional labor in its laying.

The primary object of the present invention is to provide a fastener for the strips or component members (such as units of parquetry) of composite wooden flooring whereby the latter may be laid directly upon a concrete sub-flooring, with or without the use of a mastic, and which will firmly bind the several strips together and positively prevent their separation from each other.

Among the other objects of the present invention are to provide a fastener of the character above-described which may be easily and inexpensively formed in dies out of a single strip of sheet metal; to provide a fastener of this kind which shall be so formed as to insure that any space between adjacent strips of flooring or the like shall be taken up in the process of securing the fastener in position; to provide a fastener which shall perform its intended functions without being exposed nor necessitating the piercing of the flooring by nails or other fastening elements in the process of its attachment to the sub-flooring.

To the accomplishment of these objects and such others as may hereinafter appear, the various features of the present invention relate to certain devices, combinations and arrangements of parts fully set forth herein-

after, the advantages of which will be readily understood by those skilled in the art to which the present invention pertains.

The various features of this invention will be best understood from an inspection of the accompanying sheet of drawing illustrating a preferred embodiment of the invention.

In the said drawing,

Fig. 1 is a cross-sectional view through a portion of flooring and concrete sub-flooring, embodying the present invention, and showing one strip of flooring already laid and a second strip in process of being laid;

Fig. 2 is a view similar to Fig. 1, showing both strips of flooring in laid position;

Fig. 3 is a perspective view of one end of a strip of flooring, showing the manner in which the strip is preferably milled to cooperate with the fastener; and

Fig. 4 is a perspective view of the fastener per se.

Similar reference characters indicate similar parts throughout the several figures of the drawing.

According to the present invention, each component strip 10 of flooring or the like is specially milled, as particularly illustrated in Fig. 3 of the drawing, to enable it to cooperate with applicant's improved fastener 11, particularly illustrated in Fig. 4 and described in detail hereinafter.

The sides of each strip 10 of flooring are severally milled to provide them with tongue-receiving grooves 12 extending the entire length of each side. Each strip 10 is further rabbeted to form grooves 13 along the bottom edges thereof. Grooves 13 are preferably made about one and one half times as wide as grooves 12, as shown. These grooves 12 and 13, in effect, form tongues 14 between them. The ends of tongues 14 are cut slightly so that the tongues do not extend clearly out to the sides of the strip for a purpose which will hereinafter appear.

Fasteners 11 serve the dual purpose of fastening the several strips 10 to each other and to the concrete sub-flooring 15. These fasteners are preferably bent from sheet metal in any convenient manner, as by dies 100

or the like, to the form clearly illustrated in Fig. 4.

Each fastener comprises a pair of horizontal two-ply tongues 16 adapted to be snugly received in the grooves 12 of the flooring strips, and base or supporting portions 17 extending laterally from one side of the bottom of vertical portions 18.

The vertical portions 18 are adapted to be received in the space left between shortened tongues 14 of adjacent strips of flooring, as is clearly shown in Figs. 1 and 2.

Base portions 17 are formed with longitudinally extending beads 19 intermediate the sides thereof and at a point thereon beyond the corresponding tongue 16. When these beads 19 are ultimately flattened out, as and for the purpose hereinafter described, the base portions 17 are substantially coextensive 20 with and adapted to be received in the rabbeted grooves 18.

The base portions 17 extend only from one side of the vertical members 18, and with the corresponding tongues 16 form sockets adapted to receive the tongues 14 of adjacent flooring strips. The tongues 16, vertical portions 18 and bases 17 of the fasteners 11 are continuous and longitudinally coextensive with each other.

30 The fasteners 11 may be cut into convenient lengths and cooperate with flooring strips, as shown, to provide a firm support therefor along the entire length thereof.

At the crests thereof, beads or raised portions 19 are formed with a plurality of spaced nail-receiving holes or openings 20. Substantially midway between these openings 20, the beads may be and preferably are provided with suitably shaped slits or cut-outs 40 21.

In describing the method of laying a floor according to the present invention, particular reference will be had to Figs. 1 and 2 of the drawing. Before the floor is laid, the 45 underflooring 15 is preferably first coated with a layer of mastic or similar material.

As shown in Fig. 1, strip 10a has already been laid and its fastener 11a secured in place on the underflooring by means of nails or other fastening elements 22. This leaves one tongue 16 and the flattened base 17 exposed, the other tongue 16 being received in a groove 12 of the strip 10a. A second strip of flooring 50 10b is then put in place, a groove 12 thereof receiving the said exposed tongue 16, and a rabbet 13 receiving the flattened base 17. It has been found by experience that the several strips cannot ordinarily be laid so that they will contact along the entire adjacent 55 sides thereof, but that there is always a slight space therebetween, as shown at 23 in Fig. 1.

The tongue 16 of a second fastener 11b is then inserted into the exposed groove 12 of the strip 10b with base portion 17 of the fastener 11b extending outwardly. Nails 22

are then driven into the concrete sub-flooring 15 through openings in the beads 19. This flattens the bead out and increases the effective width of the base 17. To accommodate this increase in width, the strip 10b is forced over to the left (in Fig. 1) into intimate contact with the strip 10a, thus eliminating the opening or crevice 23. Since the nails 22 penetrate into the concrete before the flattening of the beads begins, they, of course, do not give, and separation of adjacent strips to form spaces therebetween is positively prevented. This process is continued with additional strips and fasteners until the entire floor is laid. The slits or cut-outs 21 are 80 adapted to receive superfluous mastic from the surface of the mastic-covered sub-flooring, thus aiding in securely holding the fasteners down on the latter.

It will be thus seen that a simple and efficient fastener has been provided for use with flooring designed to be laid upon concrete under-floors. It is obvious that the improved fastener may be equally well used with properly milled units of parquetry in the laying of parquet flooring, and also in the laying of the panels of composite wall surfaces.

In accordance with the patent statutes, I have described the principles and particular construction of the elements and combination of the parts of my invention, and while I have illustrated and described a particular formation, I desire to have it understood that the same is only illustrative of a means of carrying out my invention in one form and that obvious changes may be made by anyone skilled in the art within the scope of the following claims without departing from the spirit of my invention.

I claim:

1. In a fastener for flooring and the like, a base portion extending laterally from the body of the fastener, and a nail-receiving raised portion extending longitudinally of said base portion intermediate the sides thereof, said raised portion being adapted to be flattened when nails are driven therethrough into the flooring or the like.

2. A device of the class described comprising a vertical body portion, a pair of tongues extending laterally in opposite directions from the top of said body portion, a base portion extending laterally from said body portion at the bottom thereof, said base portion having a bead extending longitudinally thereof and adapted to be flattened.

3. A fastener for flooring and the like adapted to be made from a single strip of sheet metal comprising a vertical member, a pair of two-ply tongues at the top of said vertical member, a base portion at the bottom of said vertical member, a raised bead extending longitudinally of said base portion, said bead

having a plurality of nail-receiving openings at the crest thereof.

4. In combination with a strip of flooring disposed upon a sub-flooring, a fastener for said strip of flooring, means to anchor said fastener to said sub-flooring, and raised means on said fastener adapted when flattened to force said strip into intimate contact with the next adjacent strip of flooring.
- 10 5. The method of laying flooring upon concrete sub-flooring comprising disposing a fastener adjacent a strip of flooring, anchoring said fastener to said sub-flooring, and then increasing the effective width of said fastener, 15 whereby said strip of flooring is forced into intimate contact with the next adjacent strip of flooring.

6. A fastening device comprising a base portion, a vertical portion attached thereto, 20 a plurality of tongues extending laterally from said vertical portion, said base portion and vertical portion being longitudinally co-extensive and continuous, and raised means on said base portion adapted, when flattened, to 25 increase the effective width of said base portion.
